UNITED STATES PATENT OFFICE.

CHARLES G. HASKIN, OF EVANSTON, ILLINOIS.

LIVE-STEAM FEED-WATER PURIFIER.

SPECIFICATION forming part of Letters Patent No. 423,606, dated March 18, 1890.

Application filed June 11, 1889. Serial No. 313,840. (No model.)

To all whom it may concern:

Be it known that I, CHARLES G. HASKIN, a citizen of the United States, residing at Evanston, in the county of Cook and State of Illinois, have invented certain new and useful Improvements in Live-Steam Feed-Water Purifiers, of which the following is a specification.

My invention relates to improvements in a live-steam feed-water purifier for steam-boilers and similar purposes; and the object of my invention is to free the feed-water from the whole or nearly the whole of the carbonates and other objectionable impurities. I effect this by bringing the water in a fine state of division into contact with highly-heated surfaces in the presence of live steam, whereby it is heated to a point sufficient to liberate therefrom most of the carbonates and some other matters held in solution. The water after being thus acted upon passes downward into the deposit-chamber, where the carbonates for the most part are retained, and it then ascends through a body of coke or other suitable filtering material, which completes the separation of any precipitated matter and renders the water clean and bright. I attain these objects by the mechanism represented by the accompanying drawings, in which—

Figure 1 is a vertical section of the purifier, a central portion broken away. Fig. 2 is a top view of the splashes or spraying-plates, and showing also the water inlet and distributing nozzles. Fig. 3 is a cross-section on line 3 3 of Fig. 1. Figs. 4 and 5 are detail views of two forms of spray-plates, and Fig. 6 is a plan view of a perforated diaphragm used in the device. Fig. 7 is a detail view of a ring used to support the spray-plates.

A is the outer cylinder or shell, which may be built of boiler-iron or steel, and has a water-inlet B, a steam-inlet C, man-holes and plates at D D D, purified-water outlet E, and blow-off F.

G is a perforated diaphragm forming the depositing-chamber H at the bottom. From G, by preference, in the center rises the pipe J, terminating in a funnel-shaped diaphragm K, fixed to angle-iron supports L. The pipe J, passing through the diaphragm G, forms the annular chamber M, in which coke or other suitable filtering material may be placed.

The diaphragm G is perforated to allow the water to ascend through the annular chamber M to the exit at E.

N is an inner cylinder, preferably constructed in annular sections O, connected by bolt-flanges P, and having a series of splashes or spray-plates Q, arranged one above the other, and staggered or alternated and connected together by the rings o o. The top ring is extended, as shown, to the same diameter as the outer cylinder, thereby causing the whole of the water to descend within said inner cylinder; also preventing the steam from circulating into the space above said inner cylinder until it has already acted upon the water in circulation therein. The ends of the splashes or spray-plates pass through rectangular apertures o' in the rings o o, said apertures providing for the admission of steam from the annular space I into the inner cylinder N. (See Fig. 7.) The splashes or spray-plates may be conveniently constructed from channel-irons, in sections similar to Fig. 4, or of corrugated sheet metal, as shown in Fig. 5, and in the latter case I use, by preference, brass or copper, and by placing them in staggered or alternating positions, as shown, the maximum spraying and heating effect upon the water is obtained. The water-inlet B may be divided into two or more nozzles R; or any equivalent arrangement, such as a perforated rose, may be conveniently used.

S is the top of the outer cylinder, fastened thereto by bolts or in any other convenient manner, whereby it can be easily removed for inspection or cleaning.

In operation I pass the unpurified water through the water-inlet B. It is divided by the nozzle R into two or more streams, which fall upon the top series of splashes or dividing-plates Q, and from these it falls upon each succeeding lower series, becoming sprayed or broken up into a fine state of division. At the same time I pass live steam through the steam-inlet C, which fills the annular space T between the inner and outer cylinders, and passes therefrom through the apertures between the splashes or dividing-plates Q, meeting and heating the finely-divided water under operation thus causing the carbonates and some other impurities in the water to fall out of solution. The mixture of water-precipi-

tates, and condensed steam then pass downward through the pipe J into the deposit-chamber H. Here most of the above-mentioned precipitates fall to the bottom and the 5 water rises through the perforated diaphragm G and the coke or filtering material contained in the annular space M to the exit E, whence it is drawn off to the boilers. During its passage through the filtering material contained 10 in M it becomes purified from any precipitate which escapes settling in the deposit-chamber H, and flows from the exit E clear and bright. The sediment which collects in the deposit-chamber H may be blown off from 15 time to time through the outlet F.

I claim—

1. In a live-steam feed-water purifier, the combination, with a closed outer vessel having an inlet-pipe for unpurified water, of an 20 interior cylinder or vessel located below the inlet-pipe and open at top and bottom, said interior vessel or cylinder having interior parallel spray-plates or splashes having their ends projected through the walls of said interior vessel or cylinder, and forming apertures for the admission of steam therein, substantially as described.

2. In a live-steam feed-water purifier, the combination, with the outer cylinder or vessel 25 having steam and water inlet pipes and

an inner cylinder having its upper end flared or extended out to the walls of the outer cylinder, and containing a series of spray-plates or splashes, substantially as and for the purpose described. 35

3. In a live-steam feed-water purifier, the combination, with the water cylinder or vessel having an inlet for unpurified water, of an interior cylinder or vessel located below the inlet-pipe and open at top and bottom, 40 and having its upper end flared or extended out to the walls of the outer cylinder to close the annular space between the two, and an inlet for steam into the said annular space.

4. In a live-steam feed-water purifier, the combination, with a closed outer vessel, of an interior cylinder or vessel open at top and bottom, and fitted internally with parallel spray-plates or splashes, and having openings in its walls for the admission of steam, 45 and its upper end flared or extended out to the walls of the outer cylinder, said outer cylinder having induction-pipes for steam and unpurified water and an eduction-pipe for purified water, substantially as specified. 55
